THROTTLE CONTROL

James M. Hicks, 3030 Bridgewater, Sausalito, Calif.
Filed Jan. 7, 1960, Ser. No. 1,007
2 Claims. (Cl. 60—54.5)

This invention relates in general to a manually-operated hydraulic system and more particularly to such a system incorporating one master cylinder and two slave cylinders, the slave cylinders being under differential spring compression tension whereby the piston of one is moved before the piston of the second.

It is an object of this invention to provide a structure as outlined above which is relatively simple in construction and which incorporates adjustment means whereby the amount of pressure required to actuate a piston of either of two substantially identical slave cylinders may be varied.

It is a further object of this invention to provide a device of the type described which incorporates means for returning the piston of the master cylinder to its original position on the release of manual pressure.

Still another object of this invention is to provide a structure of the type described above designed to afford control, by means of a single manually-operated lever, over the gear-engaging and throttle functions of an engine, a differential tension arrangement on the slave cylinders providing means for controlling each of these functions sequentially.

In the drawings:

FIGURE 1 shows the relationship of the master and the two slave cylinders;

FIGURE 2 is an enlarged side elevation, partly in section, showing the master cylinder;

FIGURE 3 is an enlarged side elevational view, partly in section, showing one of the two identical slave cylinders with part of its tension-controlling spring broken away.

Generally, this invention comprises a device wherein a single master cylinder drives more than a single slave cylinder by means of fluid pressure applied through connecting hydraulic lines. This invention incorporates improvements in both the slave cylinders and the master cylinder, making possible the control, through a single master cylinder, of two separate functions, as, a gear-engaging function and a fuel-supplying function. Means are provided for causing the individual slave cylinders to work sequentially, including resilient means exerting different compression forces secured to one end of the exterior of each of the slave cylinders and at the other end to each exposed or polished end of the piston rod of the slave cylinder, the resilient means tending to maintain the polished end of each slave piston rod in a near fully telescoped or retracted position. The master hydraulic cylinder has a piston slidably mounted therein and means on one side of said piston at one end of said cylinder for transmitting fluid pressure therefrom. The cylinder also has an orifice at a point adjacent one end thereof in the cylindrical surface thereof providing communication with the interior of the cylinder. The orifice is in an area normally occupied by hydraulic fluid when the polished end of the piston rod is exposed to a substantial extent. Means are also provided for conveying fluid to the orifice, thus to provide a continuous supply of fluid, as needed. In the preferred embodiment, the supply means comprises a chamber formed by a sleeve which may be mounted about the cylinder, both ends of which are in liquid-tight engagement with the outer wall of the cylinder itself, thus to provide a reservoir between the internal surface of the housing and the external surface of the cylinder.

Referring now to the drawings wherein like characters

2

refer to like parts throughout, there is shown a master cylinder and associated structure, generally 10. In detail, this consists of the master cylinder itself, 12, having a suitable piston 14 slidably mounted therein, the polished end 16 of the piston being surrounded by spring 17 and pivotally secured at one end of the remote throttle handle 18, also pivoted to throttle supporting rod 20, in turn mounted on bracket 22. The bracket may be mounted at any convenient point, as, for example, adjacent the position normally occupied by the operator of a boat equipped with an outboard motor. The cylinder 12 is provided with an O-ring 24 just ahead of orifice 26, thus to ensure that when the piston head has passed the orifice, a tight seal will be maintained and all pressure transmitted in the direction of fitting 28 and thence through line 30. The cylinder has a pair of flanges at either end, 32 and 34, and O-rings 36 and 38 serving as sealing means. Thus, when external housing 40 is telescoped over the master cylinder, a tight seal is ensured and the space 42 between the master cylinder and the housing serves as a reservoir of oil which may be replenished through fitting 44.

Spring 17 tends to maintain the head of the piston in a position just short of the O-ring 24 as shown in FIGURE 2. When the remote throttle 18 is moved counter-clockwise, as seen in FIGURE 1, fluid pressure is transmitted through line 30 to a T 48 which provides means for subdividing the hydraulic line so as to provide at least two separate branches 50. Each of the branches 30 terminates in structurally similar slave cylinder elements, generally 52, which can be caused to operate slightly differently. Each of these incorporates a suitable fitting 54 which secures each hydraulic line 50 to a suitable slave cylinder 56. A substantial portion of the exterior 35 of the slave cylinder is threaded, as at 58, and a ball receptacle 60 is adjustably mounted thereon. A clamp, not shown, mates with the ball receptacle and the clamp in turn is supported by a bracket which may be secured directly to a frame portion of the engine which is to be controlled by the device as, for example, an outboard motor of conventional design. Threaded about the slave cylinder is the flanged support 61, resembling a washer, for one end of compression spring 62. The threaded portion 58 of the slave cylinder supports a hexagonal 40 gland 64 on the terminal end thereof. Slave cylinder piston rod 66 passes therethrough and is sealed by O-ring 67. The rod supports a spacer 68 and a tapped motor-connecting clip 70, as well as a second flanged spring support 72. The clip is of molded plastic and has a hole 50 74 therein and a pivoted manually operated clip element 76 which is designed to exert pressure on one side of any pin which is passed through hole 74.

The device is especially designed for use with a pontoon-mounted structure having an outboard motor of the type described in U.S. Patent 2,840,832, the bracket 22 being designed for mounting on the handle bar thereof, as shown in FIGURE 1. It may be used with any outboard motor-driven boat and, for that matter, may be used in any environment where it is desired to perform two functions sequentially by the application of unidirectional hydraulic pressure, as will be seen hereinafter. In most applications, the device will be used in the control of a motor where it is desired first to engage a clutch or gears and thereafter supply fuel in varying quantities. Where the hydraulic system is used in connection with the water ski structure described in the aforementioned patent, the two devices generally designated 52 are secured to the motor by means of a clamp and bracket mating with the ball receptacle 60. The hole 74 in one of the clips 70 should be adjacent and suitable for registry with a pin controlling the clutch or gearshift arrangement of an outboard motor. The second of the slave

cylinder devices 52 is similarly mounted in such a fashion that the hole 74 may receive a pin mounted on the engine throttle. Hence, one slave cylinder will be capable of placing the motor in gear while the second will be capable of regulating the quantity of fuel fed to the motor. The spring compression tension on each of elements 52 must be adjusted as shown in FIGURE 1 so that when fluid pressure is applied through line 30, the slave piston of the lowermost element 52' will be moved first so that its slave piston (controlling the pin which engages the motor into forward gear) is moved first and the throttle slave piston thereafter moved. Gross adjustment of each of the devices 52 may be provided by screwing the ball receptacles 60 while fine adjustment placing lesser or greater tension on the compression springs 62 is provided by turning clip 70 so as to move flange support 61 toward or away from the hexagonal gland 64. The shift slave assembly 52' will be adjusted so that a lesser amount of pressure is required to move its piston than is necessary to move the piston of the throttle slave assembly 52.

Obviously, it would be possible to utilize one or more additional slave cylinder assemblies for performing additional functions, the principle of two or more spring tensions whereby to result in a sequential movement of two or more slave cylinder piston rods being easily applicable to situations requiring any number of sequential actions.

In operation, when the device is mounted as described, the remote throttle handle 18 is moved counter-clockwise, as seen in FIGURE 1, and the master cylinder transmits pressure to the two slave cylinders. This pressure activates the shift slave cylinder 52' first, thus engaging the motor into forward gear. When the throttle is pulled farther in the same direction, the piston of the master cylinder creates additional pressures which activate the throttle slave cylinder. Upon release of the handle, the spring tension provided by each of springs 62 and 17 cuts the supply of fuel and returns the motor to neutral gear. This "dead man" feature, insofar as spring 17 and one of springs 62 are concerned, may be dispensed with in certain applications.

Preferably, the orifice 26 is in the form of a slot in a plane perpendicular to that of the drawings rather than merely a small hole through the cylinder since this will permit oil to enter the cylinder 12 even when the supply in reservoir 42 is relatively low.

Certain of the outboard motors now available for use with boats, for example, the Mercury "Mark 15" and "Mark 28," models 1960, are provided with a single control handle which first engages the gears and thereafter serves as a throttle. In such an environment, the second slave cylinder of this invention may be dispensed with, one slave cylinder device 52 in itself serving as means for controlling both the gear-engaging and throttle function. The clip is modified, if necessary, to engage a rack gear which in turn controls a spur gear. This structure is conventional in outboard motors of the type afore-

mentioned and hence need not be further detailed herein. When the second slave cylinder is dispensed with and the device thus adapted for use with outboard motors having controls of this simplified type, certain of the advantages of the structure of this invention are still secured as the "dead man" feature which results from the function of spring 62 is still seen.

Suitable hydraulic fluids are Standard-Chevron Torque Fluid No. 1—type A, Automatic Transmission, and Union Oil "Turnaco," No. 200.

Obviously, many modifications and variations may be made without departing from the spirit and scope of this invention and therefore only such limitations should be imposed as are indicated in the appended claims.

I claim:

1. In a system where a single master hydraulic cylinder drives more than a single similarly sized slave cylinder by means of fluid pressure applied through connecting hydraulic lines, the improvements comprising: resilient means secured at one end thereof to the exterior of each of said slave cylinders, said means being so secured by means of supports threaded to the exterior of each of said slave cylinders, each of said resilient means being secured at the opposite end thereof to an exposed end of the piston rod of a slave cylinder and tending to maintain said exposed end of said slave piston rod in a telescoped position relative to said slave cylinder; and means on the exposed end of each of said slave piston rods for securing said exposed end to an element to be moved.
2. In a system where a single master hydraulic cylinder drives more than a single similarly sized slave cylinder by means of fluid pressure applied through connecting hydraulic lines, the improvements comprising: resilient means secured at one end thereof to the exterior of each of said slave cylinders, the means of securing said resilient means comprising a support threaded to the exterior of each of said slave cylinders, each of said resilient means being secured at the opposite end thereof to a similar supporting element fixedly secured to an exposed end of each of said slave piston rods; a ball receptacle threaded about each of said slave cylinders; and a clip fixedly secured to the exposed end of each of said slave piston rods whereby to provide means for engaging the element to be moved.
